UNITED STATES PATENT OFFICE.

VIRGIL H. BODLE, OF AKRON, OHIO, ASSIGNOR TO THE B. F. GOODRICH COMPANY, OF NEW YORK, N. Y., A CORPORATION OF NEW YORK.

SHOE-PRESSING DEVICE.

Application filed July 2, 1926. Serial No. 120,137.

This invention relates to devices for pressing shoes as in compacting the rubberized sole margin of a lasted upper and adhering it to an insole mounted on the last and underlying the said margin.

My chief object is to provide an improved device whereby the sole portion of the shoe may be more effectively and evenly pressed throughout its extent than in devices here-
10 tofore used. A further object is to provide in the improved device a sole-pressing structure adapted to be heated for the more effective compacting and adhering of the rubberized shoe parts.

15 Of the accompanying drawings:

Fig. 1 is a side elevation of the improved device in its preferred form and a lasted shoe in place therein, parts being sectioned and broken away.

20 Fig. 2 is a plan view of the sole-pressing structure and adjacent parts.

Referring to the drawings, 10 is a ram cylinder in which is mounted a ram 11 carrying on its top a plate 12 which supports 25 the sole-pressing members. Rising integrally from one side of the cylinder 10 is a bracket 13 of which the upper end portion extends laterally over the cylinder and has pivoted thereon at 14 an L-shaped hold-
30 down member 15 of which one arm is adapted to bear upon the toe portion of a shoe 16 mounted upon a last 17 and of which the other arm is adapted to bear upon the shank of the last to hold the last and shoe against 35 the upward pressure of the sole-pressing members when the latter are raised by the ram.

The sole-pressing structure comprises a heel-pressing block 18 and a toe-pressing block 19 each mounted with a ball-and-socket connection upon a hollow stud 20 mounted in and projecting upward from a plate 21 which is secured upon the upper face of the plate 12 by screws 22, 22. A 45 screw 23 has its head in the hollow stud and is screwed into the under side of the block, 18 or 19, the upper end wall of the stud being apertured to accommodate the screw with substantial tolerance so as to permit ball-and-socket movement of the block upon the stud, and a compression spring 24 is interposed between the plate 21 and the block to maintain the latter with its shaped upper face in substantially complementary

relation to the toe portion, or the heel portion, as the case may be, of a shoe placed upon the sole-pressing structure without substantial pressure. The heel-pressing block 18 and the toe-pressing block 19 are thus adapted to be pressed against the work 55 without yielding as a whole with relation to the plate 21, but are adapted to turn upon their respective studs 20 to fit against the work and apply substantially equal pressure thereto throughout their extent.

The sole-pressing structure between the heel-pressing block 18 and the toe-pressing block 19 comprises several sectional-pressing blocks 25, 26, 27, 28, 29, each formed in its lower face with a cylindrical recess such as 60 the recess 30 in which slidably fits a vertically apertured and counterbored stud 31. A screw 32 in each stud retains the block thereon while permitting sliding vertical movement of the block, and a compression 65 spring 33 is interposed between the plate 21 and each of these intermediate blocks, to press the block firmly against the work notwithstanding such non-conformity as may occur between the adjacent face of the work 70 and the group of blocks as a whole.

The several blocks are held in spaced relation by lateral studs 34, 34 projecting from one block into contact with the adjacent block, the studs thus being adapted to 75 hold the several blocks against rotary movement about their respective studs 31.

The several blocks and adjacent parts obviously are preferably of rigid and heat conductive material and they may be heated 80 in any suitable manner in order to provide a more effective compacting and adhering of the parts of the shoe, as by mounting an electrical heating element 35 under the plate 12.

In the operation of the device, the ram 11 being lowered, the work is placed upon the pressing structure and is forcibly pressed between the latter and the hold-down member 15 by elevating the ram. As the pressure is brought to bear the heel and toe portions, where the upper's margin is most gathered, receive strong pressure from the heel-pressing block 18 and the toe-pressing block 19 respectively, the said blocks not being adapted to yield bodily with relation to the ram, and yet the said blocks are permitted to turn upon their respective studs 105

so as to press the work with substantial uniformity throughout their extent.

The intermediate blocks 25 to 29 are permitted by the springs 33 to yield individually, so as to conform as a group to the contour of the work, and yet to apply adequate pressure locally to their respective parts of the work.

When the pressure has been maintained 19 for a sufficient time to effect the desired result upon the work the ram is lowered, the work removed, and the operation as described is repeated.

My invention is susceptible of modification within its scope and I do not wholly

limit my claim to the specific construction shown.

I claim:

A shoe-pressing device comprising a plurality of blocks of rigid material adapted 20 concurrently to press respective adjacent parts of the work and means for pressing the work against the blocks, yielding backing means for the blocks permitting one to yield with relation to another under the 25 force of the work, and means for heating the blocks to heat the work.

In witness whereof I have hereunto set my hand this 30th day of June, 1926.

VIRGIL H. BODLE.
